UNITED STATES PATENT OFFICE.

JOHN VOLLMER, OF ESSEN, GERMANY, ASSIGNOR TO FRIED. KRUPP AKTIENGESELLSCHAFT, OF ESSEN-ON-THE-RUHR, GERMANY.

GUN BARREL WITH A BREECH PIECE SCREWED ON AN A-TUBE.

1,412,151.

Specification of Letters Patent. Patented Apr. 11, 1922.

Application filed November 19, 1920. Serial No. 425,106.

To all whom it may concern:

Be it known that I, JOHN VOLLMER, residing at Essen, Germany, a citizen of the German Republic, have invented a certain 5 new and useful Improvement in Gun-Barrels with a Breech Piece Screwed on an A-Tube, (for which I have filed application in Germany June 2nd, 1916,) of which the following is a specification.

10 The invention relates to gun-barrels having a breech-piece screwed on an A-tube. The object of the invention is to provide means for obtaining a rigid connection between the A-tube and the breech-piece, even 15 when the breech-piece envelopes only a shorter portion of the A-tube than was hitherto usual in guns of this kind.

Referring to the annexed drawing:

Fig. 1 is a longitudinal section of the 20 parts in question of a constructional example of the invention;

Fig. 2 is a section at 2—2 in Fig. 1, seen from the left;

Fig. 3 is the top plan view, partly in section, of Fig. 1;

Fig. 4 is a longitudinal section of a second constructional example of the invention;

Fig. 5 is a section at 5—5 in Fig. 4, seen from the left;

30 Fig. 6 is the top plan view, partly in section, of Fig. 4;

Fig. 7 is a section of a detail on a larger scale.

The gun-barrel shown in Figs. 1 to 3, 35 which will be described first, consists of an A-tube A and a breech-piece B, the latter being formed with a very short jacket portion b¹ which envelopes the rear portion of the A-tube. The breech-piece has on its under- 40 side a lug b⁶ for the attachment of the recoil-brake and the running-out gear. The connection between the A-tube and the breech-piece is obtained by means of screw threads a² b². The portion b¹ of the breech- 45 piece has cut on its front face a backward slope b³ (Fig. 1), to which corresponds a front slope a³ cut on the rear face of a collar a¹ formed on the A-tube. The two slopes a³ b³ together with the cylindrical surface of 50 the A-tube enclose an annular groove of dovetailed cross section, in which two pairs of wedges C C¹ are fitted in diametrically opposed positions. The wedges C C¹ are curved concentrically with the axis of the 55 bore of the A-tube; their length is about

equal to one fourth of the circumference of a groove a⁶. The sloped faces of the wedges C C¹ which bear against the faces a³ and b³ are cone surfaces, whereas the faces c² (Fig. 3) by which the wedges bear against each other are helical surfaces perpendicular to the axis of the bore. The intervals remaining in the groove a⁶ between the two pairs of wedges are filled up by annular sectors D (Figs. 2 and 3) of rectangular cross section. A ring E extending right up to the front face of the breech-piece and which may be attached to the collar a¹ by various means, for instance by fixing screws, overlies the wedges C C¹ and the pieces D. 60 65 70

After the breech-piece B has been screwed on the A-tube, the four wedges C C¹ are placed in the annular groove a⁶ and keyed up pairwise. The wedges are retained in the groove a⁶ by their own dovetailed cross section and that of the groove a⁶. Lastly, the filling pieces D are inserted in the intervals between the pairs of wedges, and the ring E is attached to the collar a¹ of the A-tube. 75 80

By means of the above described wedge arrangement it is possible to establish such a pressure in the screw connection a² b² as to ensure a permanent rigid connection between the A-tube and the breech-piece, which cannot be loosened, for instance, by the eccentric action of the resistance set up by the recoil brake and the running-out gear. 85

In the gun-barrel shown in Figs. 4 to 6, 90 the jacket portion b¹ of the breech-piece B is provided with an annular extension b⁴, having the same outside diameter as a collar a⁴ formed on the A-tube A. The collar a⁴ and the extension b⁴ are each provided, on their end surfaces facing each other, with 95 six recesses a⁵, and b⁵. When the A-tube and breech-piece are correctly assembled, the walls of each pair of recesses a⁵ b⁵ enclose a cylindrical hollow space in which a cylindrical dowel F is inserted. The dowels F 100 are made of soft (expansible) steel. Each dowel F is perforated by an oval slot f¹ (Figs. 6 and 7) extending from one end face f² (Fig. 7) to the other, the generatrix of the slot being parallel to the axis of the dowel. 105 Into this slot is driven a double wedge formed by two wedges G G¹. The dowels F and the wedges G G¹ are retained in position by a ring H fixed in some way (for instance by shrinkage) over the collar a⁴ and 110

the extension b^4 . This modification is shown and claimed in application, No. 481,028, filed June 28, 1921.

After the breech piece has been screwed 5 on the **A**-tube, the recesses a^5 b^5 are bored and the dowels F are placed in the recesses in such manner that the oval slots f^1 of some 10 of the dowels assume the position shown on the drawing whereas the oval slots of the remaining dowels are placed at right angles thereto. Then the wedges G G^1 are inserted 15 in the dowels F and driven tightly in, thereby expanding the dowels and rigidly connecting the **A**-tube and the breech-piece. Finally, the ring H is fixed over the collar 20 a^4 and the extension b^4 .

This alternate arrangement of the dowels F and wedges G G^1 provides a reliable safeguard against the loosening of the breech-piece on the **A**-tube owing to the resistance set up by the recoil brake and the running-out gear, and also against the loosening of the **A**-tube in the breech-piece owing to the reaction of the rifling tending to rotate the 25 **A**-tube. Further, the cylindrical shape of the dowels F and the recesses a^5 b^5 facilitates the exact machining of the parts in question in the shops and ensures a uniform distribution of the pressure produced 30 by the described wedge arrangement.

Claims:

1. A gun barrel comprising a breech-piece, an **A**-tube, said breech-piece and **A**-tube being in screw-threaded engagement with one 5 another, tension devices interposed between the opposed faces of the **A**-tube and the breech-piece, and a ring surrounding said tension devices.

2. A gun barrel comprising an **A**-tube, a 0 breech-piece, said **A**-tube and breech-piece

having a screw-threaded engagement with one another, said **A**-tube and breech-piece having opposed faces shaped to form an annular groove, pairs of wedges adapted to be positioned in said groove, and means for 45 retaining said wedges in place.

3. A gun barrel comprising an **A**-tube, a breech-piece, said **A**-tube and breech-piece having a screw-threaded engagement with one another, said **A**-tube and breech-piece 50 being shaped to form an annular dovetailed groove, and wedges adapted to be positioned in said groove.

4. A gun barrel comprising an **A**-tube, a breech-piece, said **A**-tube and breech-piece 55 having a screw-threaded engagement with one another, the opposed faces of said **A**-tube and breech-piece being shaped to form an annular dove-tailed groove, pairs of wedges adapted to be positioned in said 60 groove, the opposed faces of said wedges being perpendicular to the axis of the gun barrel.

5. A gun barrel comprising an **A**-tube, a breech-piece, said **A**-tube and breech-piece 65 having a screw-threaded engagement with one another, the opposed faces of said **A**-tube and breech-piece being shaped to form an annular dove-tailed groove, two pair of wedges adapted to be inserted in said 70 groove, filling pieces adapted to be positioned between the ends of said pairs of wedges and a ring surrounding said wedges and filling pieces for securing the same in place.

The foregoing specification signed at Es- 75 sen, Germany, this 24th day of June, 1920.

JOHN VOLLMER.

In presence of—

HANS GOTTMANN,
JOHANN DÄCKERS.
